UNITED STATES PATENT OFFICE.

WILLIAM OSTENDORFF, OF UNION, HUDSON COUNTY, NEW JERSEY.

CURTAIN-POLE.

SPECIFICATION forming part of Letters Patent No. 614,748, dated November 22, 1898.

Application filed May 12, 1898. Serial No. 680,510. (No model.)

To all whom it may concern:

Be it known that I, WILLIAM OSTENDORFF, of the town of Union, in the county of Hudson and State of New Jersey, have invented new 5 and useful Improvements in Curtain-Poles, of which the following is a full, clear, and exact description.

The invention relates particularly to devices for fastening curtains to curtain-poles.

10 The object of the invention is to provide a simple and economical curtain-fastener capable of being made from a single piece of spring-wire or like material and which when applied to a pole will securely clamp a curtain thereto 15 without in the least damaging the curtain, even should the curtain be of delicate construction.

Another object of the invention is to so construct a curtain-fastener that rings or their 20 equivalent pendent objects usually employed will be dispensed with, and, furthermore, to provide a fastening that may be applied to a pole in such manner that it will be entirely hidden when the curtain is up and but a small 25 portion of the device will be visible when the curtain is down.

I will describe a curtain-pole embodying my invention and then point out the novel features in the appended claim.

30 Reference is to be had to the accompanying drawings, forming a part of this specification, in which similar characters of reference indicate corresponding parts in all the views.

Figure 1 is a front elevation of a curtain-pole having the improvement applied. Fig. 35 2 is a rear elevation of a portion of the curtain-pole and a rear elevation of the fastener applied thereto, and Fig. 3 is a vertical section taken substantially on the line 3-3 of Fig. 2.

40 The device is practically a clasp made from a single piece of wire bent upon itself to form a skeleton body A, hinge members B, and a handle C. The body A consists of a front bar 10, rearwardly-converging side bars 11, and 45 arms 12, that extend rearward from the side bars. The entire body is so shaped that its forward face will conform to the surface contour of the rear face of the pole D, to which the device is to be applied.

50 In the drawings the pole is shown as circular in cross-section. Therefore the front face of the body is concave. The handle C is carried downward and forward from the front bar of the body A, the members of the handle

being designated as 13 and 14, and are best 55 shown in Fig. 3. The hinges B are preferably constructed by forming coils 15 at the rear ends of the arms 12, the said coils being made to terminate in a pin 16, and the pins are adapted to be driven into the pole, and staples 60 may be employed, if desired, to hold the pins in place. The fastener is preferably placed at the back of the pole, and when the pole is viewed from the front only the front bar of the body and the handle will be visible, and, 65 in fact, the fastener may be so applied to the pole that only the handle will appear at the front of the pole. A projection 17, which may be in the form of a staple, is driven into the pole at the back, and the said projection 70 extends through the central portion of the body A of the fastener, as shown in both Figs. 2 and 3.

In the operation of the device the body A is forced rearward through the medium of the 75 handle C and the curtain is carried up between the curtain-pole and the body of the fastener as far as possible in direction of the spring-hinges B. The body of the fastener is then released, whereupon the said body will clamp 80 the upper portion of the curtain firmly to the back of the pole, the projection 17 serving to prevent the curtain from being disconnected from the pole when violently drawn downward, and the curtain will tear before being released from the pole. 85

It is evident that the upper edge of the curtain may be made to engage with the pole in such manner that there will be no space between the upper edge of the curtain and the 90 pole, or that the curtain may be festooned or plaited, as fancy may dictate.

Having thus described my invention, I claim as new and desire to secure by Letters Patent—

95 The combination with a curtain-pole, of a fastening device for curtains, consisting of a skeleton body conforming to a portion of the outer contour of the pole, the body having a spring-hinge connecting it with the pole, and a projection upon the pole, arranged to extend through the said body, as and for the purpose specified.

WILLIAM OSTENDORFF.
